BABY WALKER

Cedric C. Stack, Elwood, Ind.

Application August 3, 1950, Serial No. 177,460

13 Claims. (Cl. 155—24)

1

This invention relates to improvements in baby walkers and it consists in the matters herein illustrated and described and more particularly pointed out in the appended claims.

The baby walker with which the present invention is more especially concerned and which is sometimes known as a "go cart," consists of a frame work movable about on casters or the like and designed to support infant children while learning to walk so that such children accustom themselves to walking.

One of the objects of the invention is to provide a baby walker which is of a light weight, but strong and durable construction and which is of such stability that it is indeed difficult for the baby to tip the walker, in its use thereof.

Another object of the invention is to provide a baby walker which includes a seat that may be elevated from time to time to accommodate the baby in its growth and thereby adjust the height of the seat to the legs of the baby.

A further object of the invention is to provide a baby walker that includes a seat of flexible material from which the baby cannot readily escape and a frame for supporting the seat, which seat and frame are so made that the seat, when soiled, may be readily removed from the frame and replaced by a clean one.

Also it is an object of the invention to provide a baby walker which safely and comfortably confines the baby thereto, but from which it may be readily removed when in need of attention.

Again it is an object of the invention to provide a baby walker which may be shipped in a knocked down condition to occupy but a small amount of space and which may be readily assembled into its condition for use by persons of average ability.

Furthermore, it is an object of the invention to provide a baby walker that includes therein a hand hold at the front of the seat, which hand hold is so constructed and arranged relative to parts of the walker as to secure them together as a fully assembled frame while affording the support for the seat of the walker.

Also, again it is an object of the invention to provide a baby walker that includes a frame work and supporting legs that are so covered with a cushioning material that the walker cannot mar or nick furniture in the vicinity of its use.

The above mentioned objects of the invention, as well as others, together with the advantages thereof, will more fully appear as the specification proceeds.

2

In the drawing:

Fig. 1 is a perspective view of a baby walker embodying the preferred form of the invention with the seat thereof in an elevated position.

Fig. 2 is a front elevation of the walker appearing in Fig. 1 with the seat thereof in a lower position.

Fig. 3 is a horizontal sectional view through the walker as taken on the line 3—3 of Fig. 2 but with the seat frame swung to one side of the main frame and illustrating the manner in which the seat may be removed from the seat frame without a complete removal of the latter from the main frame.

Fig. 4 is a detail horizontal sectional view through one of the legs of the main frame of the walker as taken on the line 4—4 but on a scale enlarged over that of Fig. 1.

Fig. 5 is a perspective view on an enlarged scale of fragments of certain parts of the walker in an aligned position showing the same generally in the order of assembly.

Fig. 6 is a detail vertical sectional view through a part of the walker as taken on the line 6—6 and on a scale larger than that of Fig. 2 and more particularly shows the manner in which parts appearing in Fig. 5 are operatively connected together in the assembled walker.

Referring now in detail to that embodiment of the invention illustrated in the accompanying drawing, the improved walker includes a main frame made up of a pair of laterally spaced right and left hand inverted U-shaped frame members 10 and 11, each composed of a top horizontal portion 12 and front and rear end legs 13 and 14 respectively. The bottom of each leg is provided with a swiveling caster 15. Preferably each frame member 10 and 11 is made of metallic tubing but they may be made of rod stock, wood or other suitable materials, bent to suitable shape or so formed in other ways. Each member as shown is provided with a cushioning enclosure, such as for instance a rubber tubing 16 as best shown in Fig. 4. On the bottom end of each leg of said frame member is a rubber bumper 17.

The front portion of the top horizontal parts 12 of both frame members are connected together by a reach bar 18 made of tubing and formed at the top of each end with an opening 18a and at the bottom of each end with another opening 18b of such size as to fit upon a part of the portion 12 of an associated frame member 10 and 11 respectively. The openings 18a and 18b which are axially aligned, best appear in Fig. 5.

Each frame member 10 and 11 is bent outwardly from a point back of the reach bar as best appears in Fig. 3. Thus the rear legs 14 of both frame members are spaced further apart than the front legs and therefore have a greater spread. This provides such stability for the frame of the walker as a whole as will prevent tipping thereof, under the movement of the baby occupant of the walker.

Rising from the frame thus far described is an inverted U-shaped hand hold 19 which includes a horizontal cross bar 20 and depending end legs 21-21. The horizontal cross bar of this hand hold, which is bent from a piece of bar stock, is covered with a sleeve 22 of rubber to afford a good grip for the hands of the baby.

The legs of the hand hold are spaced laterally apart, the same distance as the front portions of the side frame members 10 and 11 and their bottom end portions 21a, which are of a threaded reduced diameter, are capable of passing through openings 23 in the exposed part of each portion 12 of each side frame member 10 and 11 and one of which portions best appears in Fig. 5. At the junction of each leg 21 and its extension is a downwardly facing shoulder 21b which best appears in Figs. 5 and 6.

25 indicates the seat frame of the walker made from a length of tubing bent into substantially a U-shape to have a rounded back 26 and parallel side arms 27-27 which are spaced the same distance apart as the legs 21 of the hand hold 20. In the top portion of each seat frame arm 27, near its extremity, is a threaded opening 28 to receive a set screw 29 as best appears in Figs. 5 and 6.

30 indicates a connection member employed between each leg 21 and the associated arm 27 of the seat frame. It is made from a piece of bar stock of the same diameter as the associated seat frame arm to provide a front end body portion 31 and a rear end stem 32 reduced in diameter for a snug fit in the end of the associated seat frame arm 27. A central transverse opening 33 is provided in the body and this opening is of such diameter as to permit the passage of the associated leg 21 of the hand hold therethrough. In the front end of the body 31 is a threaded opening 34 which communicates with the opening 33 and said opening takes a finger turnable screw 35. In the stem 32 of each connection member 30, near its rear end is an annular groove 32a. The distance said groove is spaced from the rear end of the body 31 is such that when said stem is inserted into the front end of a seat frame arm 27, to a point where the extremity thereof engages the rear end of the body 31 of the associated connection member 30, said groove 32a will line up with the screw 29 carried by said arm 27.

The seat which is supported by the seat frame 25 is preferably made of a waterproofed flexible material and is indicated as a whole by the numeral 36. It includes a back 37, sides 38, a bottom 39 and a front 40. The upper margin of the back and the sides are folded over and stitched thereto to provide a hem 41 of such size as to receive the back and the arms of the seat frame 25. The front 40 terminates just below the hem and where this front joins the sides. The bottom of 70 the seat is formed with leg openings 42.

Preferably the walker is shipped in a knocked down condition in a suitable box for assembly in the home of the purchaser with the aid of such simple tools as are found in nearly every home.

To assemble the various parts above described the side frame members 10 and 11 may be placed in an upright position and then the reach bar 18 applied, with the recesses 18b in its ends straddling the upper exposed parts of the portions 12 of said side frame members and with the holes 18a in said ends lined up with the holes 23 in said side frame portions.

A connection member 30 is then applied to that 10 portion of the hand hold legs 21 above the shoulders 21b thereon. By turning the associated screw 35 of the connection member, the latter is prevented from slipping off the leg portion 21. The leg portions 21a are then inserted through 15 the aligned holes and recesses 18a and 18b in the reach bar ends and through the openings 23 in the portions 12 of the side frame members so as to extend below the latter and to this portion of each leg a nut 45 is applied from below. One of 20 said nuts best appears in Figs. 5 and 6. This secures the side frame members 10 and 11, the reach bar 18 and the hand hold 20 operatively together as the main frame for the walker. At 25 this time it is best to point the stems 32 of both connection members 30 straight rearwardly and then tighten the screws 35.

After the seat has been applied to the seat frame 25 by passing the latter through the hem 41 of the seat, the front ends of the arms 27 of 30 said seat frame are caused to line up with the stems 32 of both connection members 30 until the front end extremities of said arms engage the rear end of the bodies of said connection members. In this condition the screws 29 carried by said seat frame arms 27, which now line up with the grooves 32a in the stems 32, are tightened so as to enter said grooves. This solidly but removably attaches the seat frame ends 27 to said connection members 30. By loosening the 40 screws 35 the members 30 and seat frame and seat thereon may be adjusted into the desired position on the legs 21 of the hand hold and wherein they may be locked by tightening the screw 35. When the seat 36 is in the foremost 45 position on its frame 25 the hem 41 thereof will cover the heads of both screws 29 which are of the flat head type.

By pushing the front end of the hem 41 back upon the legs 27 of the seat frame, this moves 50 the seat toward the rear of the frame and exposes the heads of said screws.

If it is desired to change the seat for a clean one this may be done in either of two ways. One way is to loosen the screws 29 far enough so the 55 seat frame may be withdrawn rearwardly and off the stems 32 of both connection members. The seat may now be worked off the seat frame from the end of one of the arms 27 thereof and a clean one applied to the frame as before mentioned. Thereafter the seat frame is applied to both stems of the connection members 30 and the screws 29 again tightened up.

Another way to change the seat is to remove 60 the end of one of the seat frame arms from its stem, as before described, and then loosen the screw 35 of the other connection member so that the frame may be swung about one of the legs 21 of the hand hold into the position shown in Fig. 3. In this position the seat may be worked off the frame from that arm that has been disconnected from its associated connection member and a new or clean one applied to the seat frame as before mentioned. The seat frame may then be swung back to its operative position 75 so that the stem enters the end of the free arm

of said frame again to be attached thereto by tightening the screw 29.

The walker is comfortable for use by babies and through the use of the same the baby soon learns to walk. As the baby grows the seat may be raised to accommodate such growth. As the legs of the walker frame are cushioned, the walker cannot mar furniture or other articles into which it may be bumped.

I claim as my invention:

1. A baby walker embodying therein laterally spaced side frame members each including a top portion and front and rear legs extending downwardly from the ends thereof, a reach bar extending transversely of and having direct connections at its ends with top portions of said side frame members, an inverted U-shaped member including a hand hold at the top and depending side legs, the bottom ends of which form parts of said direct connections, a seat support having side arms connected together at the rear, and means for operatively connecting the front ends of said side arms to said depending side legs.

2. A baby walker embodying therein laterally spaced side frame members each including a top portion and front and rear legs extending downwardly from the ends thereof, a reach bar extending transversely of and having direct connections at its ends with top portions of said side frame members, an inverted U-shaped member including a hand hold at the top and depending side legs, the bottom ends of which form parts of said direct connections, a seat support having side arms connected together at the rear, and means for operatively connecting the front ends of said side arms to said depending side legs, portions of said side frame members forwardly of said connections being disposed in parallel relation and portions of said side frame members rearwardly of said connections being splayed outwardly to space the rear legs of said frame members a wider distance apart than the front legs thereof.

3. A baby walker embodying therein laterally spaced side frame members each including a top portion and front and rear legs extending downwardly from the ends thereof, a reach bar extending transversely of and connected at its ends to portions of said side frame members, a seat support having side arms connected together at the rear, means providing a vertical pivotal connection for the front end of one of the arms of the seat support with respect to one of said side frame members and about which said support may be swung, in a horizontal plane, to bring the front end of the other arm of said support into and out of operative relation to the other side frame member, and means for detachably connecting said end of said other arm to said other side frame member when disposed in operative relation thereto.

4. A baby walker embodying therein laterally spaced side frame members, each including a top portion and front and rear legs extending downwardly from the ends thereof, a reach bar extending transversely of and connected at its ends to portions of said side frame members, a seat support having side arms connected together at the rear, means providing a vertical pivotal connection for the front end of one of the arms of the seat support with respect to one of said side frame members and about which said support may be swung in a horizontal plane to bring the front end of the other arm thereof into and out of operative relation to the other side frame

member, means for detachably connecting said end of said other arm to said other side frame member when disposed in operative relation thereto, and a seat member of flexible material having a marginal hem at the sides and rear thereof, which hem may be applied to and removed from said support when said other arm is detached from said other side frame member.

5. A baby walker embodying therein laterally spaced side frame members each including a top portion and front and rear legs extending downwardly from the ends thereof, a reach bar extending transversely of and having end portions engaged with portions of said side frame members, an upright member extending through each end of the reach bar and that portion of a side frame member with which it is engaged and operatively securing said reach bar to said side frame members, and a seat support having side arms connected together at the rear and at their front ends operatively engaged upon said upright members.

6. A baby walker embodying therein laterally spaced side frame members each including a top portion and front and rear legs extending downwardly from the ends thereof, a reach bar extending transversely of and having end portions engaged with portions of said side frame members, an upright member extending through each end of said reach bar and that portion of a side frame member with which it is engaged and operatively securing said reach bar to said side frame members, a seat support having side arms connected together at the rear, and means for attaching the front ends of the arms of the seat support to said upright members at different elevations thereon.

7. A baby walker embodying therein laterally spaced side frame members each including a top portion and front and rear legs extending downwardly from the ends thereof, a reach bar extending transversely of and having end portions engaged with portions of said side frame members, an upright member extending through each end of said reach bar and that portion of a side frame member with which it is engaged and operatively securing said reach bar to said side frame members, a seat support having side arms connected together at the rear, means providing a vertical pivotal connection for the front end of one of said arms with one of said upright members and about which connection said support may be swung in a horizontal plane to bring the front end of the other arm of said support into and out of operative engagement with the other of said upright members, and means for detachably connecting the front end of said last mentioned arm to said other upright member when in operative engagement therewith.

8. A baby walker embodying therein laterally spaced side frame members, each including a top portion and front and rear legs extending downwardly from the ends thereof, a reach bar extending transversely of and having end portions engaged with portions of said side frame members, a hand rail disposed above said reach bar and having depending end legs, secured to said reach bar and to said side frame members respectively, and a seat support having side arms connected together at the rear and at their front ends operatively engaged with said end legs of said hand rail.

9. A baby walker embodying therein laterally spaced side frame members each including a top portion and front and rear legs extending down-

wardly from the ends thereof, a reach bar extending transversely of and having end portions engaged with portions of said side frame members, a hand rail disposed above said reach bar and having depending end legs, bottom portions of which extend through the end portions of said reach bar and through portions of said side frame members with which they engage, a seat support having side arms connected together at the rear, and means for detachably connecting the ends of the side arms of said seat support to said end legs of the hand rail.

10. A baby walker embodying therein laterally spaced side frame members, each including a top portion and front and rear legs extending downwardly from the ends thereof, a reach bar extending transversely of and having end portions engaged with portions of said side frame members, a hand rail disposed above said reach bar and having depending end legs, bottom portions of which extend through the end portions of said reach bar and through portions of said side frame members with which they engage, a seat support having side arms connected together at the rear, connection members mounted one on each leg of the hand rail and each including a rearwardly extending stem, and means for detachably connecting the end of each arm of the seat support to an associated stem.

11. A baby walker embodying therein laterally spaced side frame members each including a top portion and front and rear legs extending downwardly from the ends thereof, a reach bar extending transversely of and engaged at its ends upon a portion of both side frame members, a 35 hand hold having end legs with a reduced diameter lower threaded portion connected to the associated leg by a shoulder, said reduced diameter lower portion of each leg of the hand hold extending through an associated end of said reach bar and portion of said side frame member engaged thereby, a nut on each lower portion of each hand rail leg for drawing the parts tightly together with each end portion of the reach bar engaged by said shoulder on an associated leg of the hand hold, and a U-shaped seat frame having side arms, each connected to a leg of the hand hold for adjustment vertically thereof.

12. A baby walker embodying therein laterally spaced side frame members each including a top portion and front and rear legs extending down-

wardly from the ends thereof, a reach bar extending transversely of and engaged at its ends upon a portion of both side frame members, a hand hold having end legs with a reduced diameter lower end threaded portion connected to the associated leg by a shoulder, said reduced diameter lower end portion of each leg of the hand hold extending through an associated end of said reach bar and side frame member portion engaged thereby, a nut on each lower end portion of each hand rail leg for drawing the parts tightly together with each end portion of said reach bar engaged by a shoulder on an associated leg of the hand hold, a connection member mounted on each leg of the hand hold, and each connection member including a rearwardly extending portion, a U-shaped seat frame having side arms with the free end of each side arm having a telescopic engagement with the rearwardly extending portion of each connection member, and means for releasably attaching the free end of each side arm to its associated rearwardly extending portion of each connection member.

13. A baby walker embodying therein two side frame members each of inverted U shape in side elevation, means holding said frame members in lateral spaced relation, an inverted U-shaped member including a hand hold at the top and depending side legs, one fixed at the bottom to each side frame member, a seat supporting frame of U shape in plan, the legs of said U-shaped seat frame being secured to said side legs of said inverted U-shaped member.
